UNITED STATES PATENT OFFICE.

THEODOR LANGKOPF, OF UNTERTURKHEIM, GERMANY.

APPARATUS FOR HERMETICALLY CLOSING PRESERVE GLASSES.

Application filed September 4, 1923. Serial No. 660,904.

This invention relates to an apparatus comprising a pumping device and a device for hermetically closing in a few moments preserve glasses of any construction uniformly and securely.

In the drawings a form of construction of the invention is shown by way of example.

Fig. 1 is a side elevation of the apparatus.

Fig. 2 is a plan view of the same.

Fig. 3 is a longitudinal section showing the closer in operation.

Fig. 4 shows in section the pumping device with the pump piston in the position at the right hand end.

Fig. 5 is a similar view with the pump piston in the left hand position.

The apparatus for hermetically closing preserve glasses consists essentially of two main parts, the closing device and the double acting pump. The apparatus serves for the preserving of vegetables, fruit or the like without heat in withdrawing from the receptacle *a*, the lid of which is closed, the air with the aid of a double acting pump piston *7* so that after the lid *h* is removed the preserve glass *G*, which has been closed by the outer air, may be removed at once.

The receptacle *a* which may be fixed by means of clamps *b* on a table plate *T* or the like has an upper edge *c* which is bent over in outward direction to form a bead and it has further two vertical supports *d* with indentations *e*, said supports being arranged at opposite sides of the receptacle. The indentations serve to receive cylindrical journals *g* at the ends of a crank shaft *f* which is thus securely guided. The crank shaft *f* is further connected with the lid *h*, said lid being adapted to move elastically in inward and outward direction, by means of collars *i* placed around the eccentric part of shaft *f* at convenient distances apart in connection with the lid *h* by means of rivets *k* or the like. The rotating movements of shaft *f* are produced with the aid of a crank handle *l*. In a central cavity *m* of the lid *h* a packing *n* of leather or any convenient material is embedded which has an air hole *o*. The eccentric part of shaft *f* is cut out at *p* so that when the handle *l* stands upright the hole *o* of the packing is free so that the atmospheric air can flow into the receptacle *a*. In the lower part of the receptacle *a* a double-acting pump is arranged which works silent and free from shocks. This pump serves to prevent that during the production

of the vacuum the air in the receptacle be stopped as shocks or stopping of the air at the production of the vacuum would have an undesirable action on the preserved fruit.

In the receptacle *a* a transverse pump cylinder *2* is mounted which has a nut *3* at one end in which the piston rod *4* is guided through the intermediary of packings *5* and of a stuffer *6*.

At the end of the piston rod leather disks *7* are removably mounted by means of a screw *8*.

On a sheet metal plate *9* arranged above the pump cylinder *2* the preserve glass *G* (Figs. 4 and 5) is mounted.

The double-acting pump is closed by ball valves which are independent of one another.

At the right and left of the receptacle *a* curved tubes *10*, *11* respectively connect said receptacle with the pump cylinder *2* through the intermediary of a tubular socket *12*,

13 respectively serving as valve casings. In the tubular sockets *12*, *13* balls *14*, *15* are enclosed which serve as valves and the stroke of which is limited by studs *16*, *17*.

The rear end of the pump cylinder *2* is formed by a locking nut *18* which, by means of an outward directed tubular socket *19* and of a cross pin *21*, imprisons a ball *20* acting as a valve.

Upon the opposite end of the pump cylinder a tubular socket *22* is arranged in which a ball *23* with pin *24* is enclosed.

The operation of the apparatus is as follows:—The glass *G* which contains the fruits or the like is placed upon the sheet metal plate *9* in the receptacle *a*, the lid of the

preserve glass being in place, whereupon the lid *h* is placed on the receptacle *a* the end parts of the shaft *f* being inserted into the indentations *e* of the supports *d*.

By lowering the hand lever *l* the shaft *f* is turned and the crank of said shaft produces an airtight closing of the receptacle as the circumference of shaft *f* covers air-tightly the air hole *o*.

If the piston of the pump is operated for about twenty times the balls *14* and *20* are pushed outward when the piston advances (Fig. 5) and the balls *15* and *22* are drawn in inward direction towards the studs *17* and *24* whilst at the return stroke of the piston the balls are moved in

inverse direction. In this manner a sucking action is produced in the receptacle *a* which remains constant during the pumping and avoids any sudden movement of the air.

If the lever *l* is turned up into the position shown in Fig. 1 in dotted lines the compression of the rubber lining *h'* with

regard to the annular bead c is slightly loosened and the air hole o is uncovered by the cut out part p of the shaft so that the outer air can flow into the receptacle a , whereby the lid of the preserving glass G is strongly pressed on.

I claim:-

1. Apparatus for hermetically closing preserve glasses comprising in combination 10 a receptacle designed to receive the preserve glass, two vertical supports at opposite sides of said receptacle having incisions in the parts projecting over the rim of said receptacle, a lid for said receptacle having a central air hole, a crank shaft on said receptacle the ends of which engage with said incisions, means for rotating said crank shaft so that its crank simultaneously presses upon the lid and closes the air hole, 15 said crank having a transverse slot, an air pump in the lower part of the receptacle, curved suction pipes connecting the ends of the pump cylinder with the interior of the receptacle, and ball valves in said curved pipes, said crank shaft rotated by the said means uncovering at a determined position by its said transverse slot the air hole so 20 that air is admitted into the receptacle.
2. Apparatus for hermetically closing 25 curved pipes.

preserve glasses comprising in combination a receptacle designed to receive the preserve glass, two vertical supports at opposite sides of said receptacle having incisions in the parts projecting over the rim of said receptacle, a lid for said receptacle having a central air hole, a rubber packing ring surrounding said central air hole, a crank shaft on said receptacle the ends of which engage with said incisions, means for rotating said 30 crank shaft so that its crank simultaneously presses upon the lid and closes the air hole, 35 said crank having a transverse slot, an air pump in the lower part of the receptacle, curved suction pipes connecting the ends of the pump cylinder with the interior of the receptacle, and ball valves in said curved 40 pipes, said crank shaft rotated by the said means uncovering at a determined position by its said transverse slot the air hole so 45 that air is admitted into the receptacle.

In testimony whereof I affix my signature.

THEODOR LANGKOPF.
